DROP RATE SENSOR FOR INTRAVENOUS FEEDING SYSTEMS OR THE LIKE

Richard A. Cramer, La Jolla, Calif., assignor to Life Electronics, Inc., La Jolla, Calif., a corporation of California

Filed Nov. 27, 1967, Ser. No. 9,555

Term of patent 14 years

(Cl. D83—1)

FIGURE 1 is a front perspective view of a drop rate sensor for intravenous feeding systems or the like showing my new design;

FIGURE 2 is a top plan view of the drop rate sensor shown in FIGURE 1;

FIGURE 3 is a right side elevational view of the drop rate sensor shown in FIGURE 1; and

FIGURE 4 is a rear elevational view of the drop rate sensor shown in FIGURE 1.

The broken lines representing portions of the intravenous feeding system are shown for illustrative purposes only.

I claim:

The ornamental design for a drop rate sensor for intravenous feeding systems or the like, as shown and described.
